Patented Oct. 17, 1916.

FIG. 1.

UNITED STATES PATENT OFFICE.

ALFRED Z. BAKER, OF LEONIA, NEW JERSEY, ASSIGNOR TO ILLUSTRATED POSTAL CARD AND NOVELTY COMPANY, OF NEW YORK, N. Y., A CORPORATION OF NEW YORK.

TOY.

1,201,793.

Specification of Letters Patent.

Patented Oct. 17, 1916.

Application filed October 28, 1915. Serial No. 58,436.

To all whom it may concern:

Be it known that I, ALFRED Z. BAKER, a citizen of the United States, and a resident of Leonia, in the county of Bergen and State 5 of New Jersey, have invented a new and Improved Toy, of which the following is a full, clear, and exact description.

My invention relates to a toy vehicle the entire body of which is formed of a fold-10 able blank.

An object of the invention is to provide a simple and inexpensive toy which can be easily and quickly folded into a predetermined vehicle.

15 A further object of the invention is to provide a wheeled vehicle which is propelled through the medium of an elastic member adapted to be wound on an axle.

With the above and other objects in view, 20 the nature of which will more fully appear as the description proceeds, the invention consists in the novel construction, combination, and arrangement of parts as herein fully described, illustrated and claimed.

25 In the accompanying drawings, forming part of the application, similar characters of reference indicate corresponding parts in all the views.

Figure 1 is a perspective view of the toy 30 vehicle; Fig. 2 is a longitudinal section therethrough; Fig. 3 is a plan view of the blank from which the entire body of the vehicle is made; Fig. 4 is a plan view of the strips forming the running boards for the 35 vehicle; and Fig. 5 is a plan view of the disks.

Referring to the drawings, the blank shown in Fig. 3 is cut out of any suitable material which can be easily folded. The longitudinal portion or panel 6, bordered by the 40 lines $a-b-c-d$ forms the bottom of the vehicle. It is bordered on each side by a longitudinal portion or panel 7 and 8, forming the sides of the vehicle, the portion 7 being foldable on line $a-d$ and the portion 8, on the line $b-c$. Extending longitudinally from the panel 6 are end portions or 45 panels 9 and 10 respectively, the portion 9 forming the front panel of the vehicle and foldable on line $c-d$, the portion 10 forming the rear panel and foldable on line $a-b$. The longitudinal panel 8 is provided with laterally extending panel portions 11 and 50 12 foldable longitudinally on lines $e-f$ and $g-h$ respectively. The lateral panel 11 is 55 adapted to bind the side panels 7 and 8 to the end panel 10 and form the seat compartments of the vehicle. The panel 12 is also adapted to bind the side panels 7 and 8 to the front panel 9 to form the engine 60 portion of the vehicle. The lateral panel 11 has a cut-out 13 whereby a seat portion 14 is formed similar to the seat portion 15 provided at the end of the extension 11 adjacent the extension 12. The seat portions 65 14 and 15 are foldable transversely on lines $i-j$, $k-l$, $f-m$ and $n-o$ respectively. The lateral extension 11 has also an end portion or panel 16 foldable transversely on the line 70 $e-p$. A longitudinal portion 17 of the extension which unites the seat portion 15 with the main portion of the lateral extension 11 is foldable longitudinally on line $p-m$.

The lateral extension 12 has an end portion 18 foldable on the transverse line $g-q$ 75 to form the wind shield. The lateral portion 12 is also foldable longitudinally on lines $g-r$, $g-s$ and $g-t$. The front panel 9 of the vehicle presents two substantially circular corner portions 19 which take the place 80 of the head lights. It has also a semicircular portion 20 between the portions 19 adapted to engage a slot 20' provided in the lateral panel section 12. It has also side portions 21 foldable on lines $c-c'$ and $d-d'$ and 85 adapted to fit between the side panels 7 and 8. The rear panel 10 has also side portions 21' foldable on lines $b-b'$ and $a-a'$, also adapted to fit between the side panels 7 and 8. It has a central semi-circular tongue 22 90 for engaging a slot 22' in the lateral panel 11. The portion 16 of the lateral panel 11 has side tongues 23 and 24 for engaging slots 23' and 24' respectively in the side panels 8 and 7 95 respectively. The seat section 14 of the panel 11 has the corner tongues 25 and 26 for engaging slots 25' and 26' in the side panels 8 and 7 respectively and the portion 17. The seat portion 15 has also corner tongues 27 and 28 for engaging slots 27' and 28' in the side panels 8 and 7 respectively. The portion 17 of the lateral panel 11 has an angularly disposed tongue 29 for engaging a slot 29' in the side panel 7. A similar tongue 30 is provided on the longitudinal 100 edge of the lateral panel 12 for engaging a slot 30' in the side panel 7. The engagement of the tongues 29 and 30 with their re-

spective slots prevents the interengaged panels from parting, that is to say, forms the locking means for the folded body.

The side panels 7 and 8 are provided with openings 31 adjacent the front and rear thereof for the axles 32. The ends 33 of the axles 32 are angular so that a disk 34 forming a wheel engaging the end is constrained to revolve with the axle. The disk 34 has foldable portions 35 where it engages the axle so as to increase the bearing surface of the disk on the axle. The side panels 7 and 8 are provided with slots 36', 37' and 38' adjacent their folding lines for receiving tongues 36, 37 and 38 of corresponding strips 39 adapted to represent the mud guards of the vehicle. The strips 39 are foldable on lines *u*, the end portions being provided with angular tongues 40 of which one is adapted to engage the slot 25' or 26' according to which side the mud guard is to be placed, and the other to engage the slots 40' provided in the side panel 8 and the lateral extension 12. A cut-out 41 is provided in the side panel 7 to coöperate with the slot 40' of the lateral extension 12.

The folded vehicle is propelled through the medium of an elastic member 42, one end of which is secured to the rear axle 32 and the other end, preferably, to the front panel 9. The circular portions 19 and 20 of the front prevent the front from collapsing when the member 42 is stressed. A circular opening 43 is provided in the bottom panel 6 at the rear thereof to facilitate the engagement of the end of the elastic member 42 with the rear axle. A circular disk 44, resulting from the cut-out 43, is used as a steering wheel for the vehicle. It is mounted on a stem 45 which is engaged by a portion 46 of the blank and also by an opening 47 provided in the bottom panel 6. The portion 46 forms part of the side panel 8 and is foldable on the transverse line *v*—*g*.

To shape the blank into the vehicle, all parts thereof being foldable away on the lines indicated with the exception of the parts foldable on the lines *k*—*l*, *n*—*o* and *g*—*q*, which are foldable in the opposite direction, the tongues or lugs are engaged in the corresponding slots with the angularly disposed tongues 29 and 30 locking the folded blank and preventing the disengagement of the interengaging parts. The axles are then passed through the corresponding openings 31 and the wheels 34 thrust upon the angular ends 33, the flaps 35 in the center of the wheel gripping the angular end of the axle. The elastic member 42 is then secured, as previously stated, and by winding the rear wheel in the direction indicated by the arrow in Figs. 1 and 2 and holding the wheels to prevent loss of power, the same may be caused to roll through a distance of from twenty-five to thirty-five feet if placed

on a smooth floor. It is self-evident that the distance moved depends on the tension given to the flexible member and on the smoothness of the floor on which the vehicle is placed to run.

I claim:

1. In a toy vehicle, a blank having longitudinally foldable portions adapted to form the sides of the vehicle body and end portions foldable transversely and adapted to form the front and rear of the vehicle body, and lateral extensions from one of said longitudinally foldable portions foldable longitudinally of said longitudinal portion to engage the other longitudinal portion of the blank, each of said end portions having means for engaging the adjacent lateral extensions, one of said lateral extensions having portions foldable transversely thereof adapted to form seats in said body of the vehicle.

2. In a toy vehicle, a blank having a longitudinal panel adapted to form the bottom of the vehicle, said blank having a longitudinally foldable panel on each side of said bottom panel, said blank having an end panel at each end of the bottom panel foldable transversely of said bottom panel, one of the longitudinally foldable side panels having lateral extensions foldable longitudinally thereof to engage the other side panel, said lateral extension having means for engaging said other side panel and locking the blank in folded position, one of the lateral extensions having transversely foldable portions adapted to form seats between the side panels above the bottom panel, the other of said lateral extensions having longitudinally and transversely foldable portions adapted to form the engine end of the vehicle, said end panels having means for engaging the adjacent lateral extensions of the blank.

3. In a toy vehicle, a blank having longitudinally foldable portions adapted to form the sides of a vehicle body, and transversely foldable portions adapted to form the ends of a vehicle body, said transverse foldable portions having longitudinally foldable parts adapted to fit between the longitudinally foldable parts of the blank, one of said longitudinally foldable parts having lateral extensions foldable longitudinally to engage the other longitudinally foldable portion and said transverse foldable portions, one of said lateral extensions adapted to present seat sections between said longitudinally foldable portions of the blank.

4. A foldable automobile toy comprising a blank having a longitudinal panel forming the bottom of the body, said blank having a side panel to each side of said bottom panel foldable longitudinally thereof, said blank also having an end panel at each end of the bottom panel foldable trans-

versely thereof, one of said end panels adapted to present the front of the automobile, including the head lights, said blank having lateral extensions from one of the 5 said panels foldable longitudinally thereof to engage the other side panel, said lateral extensions having means for engaging said side and end panels to maintain the blank in a folded position, one of said lateral 10 extensions having transversely foldable portions adapted to present seat sections between the side panels over the bottom panel, the other lateral extension having longitudinally foldable portions to form the engine 15 housing of the body, said lateral extension having also a transversely foldable portion for presenting the wind shield, foldable strips having means for engaging the side panels and adapted to form the mud guards for 20 the body, revoluble axles for engaging the side panels adjacent the end panels, disks engaging the axles and constrained to revolve therewith, and an elastic member having one end thereof secured to the blank 25 and the other end to one of said axles.

5. A foldable toy, the body of which is formed of a single blank, said blank having a longitudinal panel forming the bottom of the vehicle and side panels foldable longitudinally of the bottom panel, said blank 30 having end panels forming extensions from the bottom panel and foldable transversely thereof, one of said side panels having lateral extensions foldable longitudinally of 35 said side panel, said lateral extensions having longitudinally and transversely foldable portions adapted to complete the toy structure between the end and side panels, said lateral extensions having means for 40 engaging the side and end panels whereby the shaped blank is retained in the folded position.

6. A foldable toy comprising a blank having longitudinally and transversely foldable 45 portions, one of said longitudinal portions having lateral extensions foldable longitudi-

nally and transversely for completing the structure between said longitudinally and transversely foldable portions, said lateral extensions having means for engaging the 50 longitudinally and transversely foldable portions of the blank to retain the same in folded position, axles projecting through the longitudinally foldable portions and mounted to revolve therein, disks carried by the 55 ends of the axles and constrained to revolve therewith, and an elastic member one end of which is secured to one of the transversely foldable portions and the other end to the axle remote from said transverse portion, 60 said transverse portion having means adapted to extend beyond the adjacent longitudinally foldable portions when said blank is folded, and whereby said transverse portion is prevented from collapsing when said 65 elastic member is stressed.

7. A foldable toy vehicle comprising a blank having longitudinally and transversely foldable portions, one of said longitudinal portions having lateral extensions 70 foldable longitudinally and transversely for completing the structure between said longitudinally and transversely foldable portions, said lateral extensions having means for engaging the longitudinally and transversely 75 foldable portions of the blank to retain the same in folded position, a running gear connected to the so-folded blank, and an elastic member, one end of which is secured to one of the transversely foldable portions and the 80 other end to the running gear, the said transverse portion having means extending across the longitudinally foldable portions preventing the collapsing of said blank when said elastic member is stressed. 85

In testimony whereof I have signed my name to this specification in the presence of two subscribing witnesses.
